INVENTOR

JOSEPH MONTGOMERY

BY

Middle & Marquon
ATTORNEYS

UNITED STATES PATENT OFFICE.

JOSEPH MONTGOMERY, OF WEST NEW YORK, NEW JERSEY.

CLASP.

Application filed October 6, 1921. Serial No. 505,772.

To all whom it may concern:

Be it known that I, JOSEPH MONTGOMERY, a citizen of the United States, and a resident of West New York, county of Hudson, and 5 State of New Jersey, have invented certain new and useful Improvements in Clasps, of which the following is a specification.

My invention relates to an improved clasp for lingerie, ties and other articles of apparel.

1 An object of my invention is the provision
of a clasp comprising a structure wherein
the fabric may be securely clasped without
danger of injury to the same, this object be-
15 ing accomplished by providing a clasp, the
gripping or clasping portion of which is
free of teeth or other uneven gripping sur-
faces.

A further object of my invention is the provision of a clasp of a type wherein the gripping surfaces are so arranged that the clasp may be used with equal facility with both wide and narrow fabrics.

To the end that the objects above enumerated and such other objects as may be hereinafter pointed out may be attained, I have an improved clasp which in general comprises a pair of arms preferably of resilient material, one of said arms being provided with a turned-over flange extending transversely of the clasp. This flange when turned over constitutes an unbroken gripping member cooperating with the other arm of the clasp, so that when the clasp is closed the fabric will be firmly gripped.

I have illustrated several embodiments of my invention in the accompanying drawing, wherein,—

Fig. 1 is a perspective of a clasp constructed in accordance with my invention, the clasp being in open position;

Fig. 2 is a side elevation of the clasp of Fig. 1, the clasp in this figure being in closed position;

45 Fig. 3 is a section on the line 3-3 of Fig. 2, looking in the direction of the arrows;

50 Figs. 4 and 5 illustrate a modified form of my improved clasp, Fig. 4 being a side elevation of the same while Fig. 5 is a section taken on the line 5-5 of Fig. 4;

Figs. 6 and 7 illustrate a further modification, Fig. 6 being a side elevation and

Fig. 7 a section substantially on the line 7-7 of Fig. 6; and

Figs. 8 and 9 are more or less views in perspective of two further modifications.

Referring to the drawings in detail and first of all to Figs. 1 to 3 inclusive,—1 and 2 designate respectively a pair of arms of any suitable resilient material such as metal for example, although in some instances it may be desirable to employ celluloid for instance. In the case of metal the same can be plated with gold, silver or other precious metal and ornamented as by embossing or engraving or in any desired manner. For the purpose of illustration or by way of example I have shown the arms 1 and 2, in fact the entire clasp struck from a single piece of material, these arms being so constructed as to have relative movement to permit of the reception of the material to be clasped.

The ends of the arms 1 and 2 are preferably bent over as indicated at 3 and 4 so that the clasp when closed will remain in that condition, this action being aided by the resiliency or spring of the material of which the clasp is made. This locking feature just described is illustrative only and not in any sense definitive inasmuch as obviously numerous other methods of locking could be employed if desired. 75 80

The arm 2 of the clasp is provided with a bent-over portion designated 5 and which I will for convenience hereinafter term a flange. This portion of the arm is bent inwardly or transversely of the clasp and extends substantially the entire length of the arm 2 and longitudinally thereof to provide a flange with what may be termed a "floating" edge and inasmuch as this bent-over portion lies substantially parallel to but spaced from the upper surface of the arm by which it is carried and lies beneath the under surface of the arm 1 a resilient gripping member is provided which, cooperating with the arm 1 when the clasp is closed, affords a convenient construction for gripping the fabric and holding the same without danger of injury thereto.

The modification of Figs. 4 and 5 comprises arms 6 and 7 of resilient material. These arms are likewise preferably struck from a single piece of material and are pro-

vided with locking means 8. The upper arm 6 is provided on its under side with a longitudinally extending groove 9 which is preferably made by bending the material along the line of the groove. The lower arm 7 is provided with a flange 10 extending longitudinally of the arm for practically the entire length thereof. This flange is bent transversely of the arm and 10 the inner edge thereof is bent upwardly as indicated at 11, so as to form a resilient gripping edge cooperating with the groove 9 already referred to. Here again I provide continuous gripping surfaces, to wit, the 15 groove 9 and the edge of the flange 10 by which fabric may be gripped and securely held.

The clasp of Figs. 6 and 7 comprises an arm 12 similar to the arm 1 of the clasp of Fig. 1, an arm 13 and locking means 14. The arm 13 is provided with a flange 15 extending substantially the length of the clasp. This flange is bent transversely to the clasp and then given a reverse bend as indicated 25 at 16. The upper face of the flange is substantially flat and lies practically parallel to the under surface of the arm 12. I thereby secure good gripping surfaces for receiving the fabric to be clasped, and by giving 30 the flange a reverse bend as described, the gripping action is slightly increased.

In Fig. 8 I have shown a clasp comprising arms 17 and 18 and locking means 19 similar to the arms 1 and 2 and the locking means of Fig. 1. The arm 18 is provided with a flange 20 extending practically the length of the arm, this flange being bent transversely of the arm in the same manner as described in connection with Fig. 1. This 40 flange 20, it will be seen, is provided with an opening 21 which increases the resiliency of the gripping member and which enables a heavier material to be employed in the construction of the clasp than is practicable 45 with the clasp of Fig. 1.

Fig. 9 is similar in all respects to the clasp of Fig. 8 with the exception of the flange thereof. Here I provide arms 22 and 23, locking means 24 and a flange 25. This flange is bent transversely of the arm and cut out as indicated at 26, a reinforcing or strengthening rib 27 being provided to stiffen the flange. This reinforcing member, it will be understood, is an integral part of 50 the flange 25 and is the same as the members 28 and 29, the flange being cut out at each side of said member 27.

It will be seen from the foregoing that I have provided an improved clasp capable 55 of gripping and securely holding a strip of

fabric, whether wide or narrow, without employing gripping means which are liable to injure the fabric.

It will be seen furthermore that by providing gripping surfaces extending continuously substantially the entire length of the clasp, no particular care is necessary in applying the clasp to the fabric to be gripped.

What I claim is:

1. A clasp comprising a strip of material folded upon itself to form a pair of spaced-apart arms, a portion of one of said arms being bent transversely to form an overhanging flange having a floating edge, said flange extending transversely and longitudinally of the arm, the upper side of said flange and the under side of the arm above it together constituting cooperating gripping surfaces.

2. A clasp comprising a pair of arms, a flange of resilient material and having a floating edge carried by one arm and cooperating with the other arm to grip material to be clasped, said flange being bent in a direction transverse of the arm by which it is carried and extending continuously throughout the length of the arm.

3. A clasp comprising an elongated strip of material folded upon itself to form a pair of arms overlying each other, said arms at their free ends being bent over to form a lock for holding the arms in closed position, a resilient flange having a floating edge and integral with one of said arms, said flange being folded back and transversely of the arm with which it is integral so that the upper face thereof extends longitudinally of and lies substantially parallel with the under side of the other arm.

4. A clasp comprising a pair of arms, means for locking said arms to each other and a flange extending longitudinally of the clasp carried by one of said arms and having a floating edge, said flange being provided with an opening therein and being bent inwardly and transversely of the clasp but spaced from the arm by which it is carried, the upper side of said flange cooperating with the under side of the other arm to form a gripping medium.

5. A clasp comprising two arms one of which has a bent-over portion extending longitudinally thereof and provided with a floating edge to provide a resilient flange bent transversely of the clasp and extending substantially the entire length of the clasp.

This specification signed this 5th day of October, 1921.

JOSEPH MONTGOMERY.
